UNITED STATES PATENT OFFICE.

ALFRED W. SIMONSON, OF MINNEAPOLIS, MINNESOTA.

WINDOW-VENTILATOR.

1,256,836.

Specification of Letters Patent. Patented Feb. 19, 1918.

Application filed May 11, 1917. Serial No. 167,896.

To all whom it may concern:

Be it known that I, ALFRED W. SIMONSON, a citizen of the United States, residing at Minneapolis, in the county of Hennepin and State of Minnesota, have invented certain new and useful Improvements in Window-Ventilators; and I do hereby declare the following to be a full, clear, and exact description of the invention, such as will 10 enable others skilled in the art to which it appertains to make and use the same.

My invention has for its object to provide an extremely simple and highly efficient ventilator for windows; and, to this end, it 15 consists of the novel devices and combinations of devices hereinafter described and defined in the claims.

In the accompanying drawings, which illustrate the invention, like characters indicate like parts throughout the several views.

Referring to the drawings,

Figure 1 is a fragmentary perspective view of a window having the invention incorporated therein; and

Fig. 2 is a view in transverse vertical section with some parts shown in different positions by means of broken lines.

The numeral 3 indicates a window frame having mounted therein for vertical sliding movement upper and lower sashes 4 and 5, respectively. A lock 6 is provided for securing the two sashes closed. On each side of the lock 6, the inner faces of the meeting-rails of the sashes 4 and 5 are cut away to afford apertures 7 to permit the passage of air into the room. Formed in the top faces of the meeting-rails of the sashes 4 and 5 and surrounding each aperture 7, is a marginal recess 8.

A cover plate 9 is provided for each aperture 8 and fitted, one in each of the recesses 8 with its upper face flush with the upper surfaces of the meeting-rails of the sashes 4 and 5. These cover plates 9 overlap the joint between the meeting-rails of the sashes 4 and 5 and, as shown, are secured by hinges 10 to the meeting-rail of said upper sash. The hinges 10 are constructed to work under sufficient friction to support the cover plates

9 in various different open positions, as indicated by broken lines in Fig. 2.

Cut in the intermediate portion of the free edge of each cover plate 9, is a thumb-hold 11 by means of which an operator may get hold of said cover plate to lift the same. By 55 setting the cover plates in different open positions, the supply of fresh air admitted through the apertures 7 may be regulated, at will. In locating one of the apertures 7 on each side of the sash lock 6, said sash lock is not interfered with, in any respect. The size of the aperture 7 may be varied, at will, depending upon the maximum amount of air to be admitted to the room. In forming the aperture 7 in the opposing faces of 65 the meeting-rails, very little work is required and said meeting-rails are not weakened to any appreciable extent. In some instances, one aperture 7 may be large enough to admit the required amount of fresh air. When the 70 cover plates 9 are closed, the same are entirely out of sight, thus not marring the appearance of the window, and they leave the top surfaces of the meeting-rails perfectly smooth, so that there is no chance 75 for the accumulation of dust.

What I claim is:

1. In a window ventilator, the combination with upper and lower window sashes, one of the meeting-rails of said sash having 80 its inner face cut away to form an air passageway between the meeting-rails, of a cover plate hinged to one of the meeting-rails and arranged to close the passageway.

2. In a window ventilator, the combination with upper and lower window sashes having the inner faces of their meeting-rails cut away to form an air passageway which extends completely through both thereof, of a single cover plate hinged to one of the 90 meeting-rails and arranged to close the passageway.

In testimony whereof I affix my signature in presence of two witnesses.

ALFRED W. SIMONSON.
